UNITED STATES PATENT OFFICE.

WILLIAM F. HEBRANK, OF HIGHLAND, ILLINOIS.

FEEDING MECHANISM FOR CAN-MAKING MACHINES.

No. 913,886.

Specification of Letters Patent.

Patented March 2, 1909.

Application filed March 6, 1908. Serial No. 419,417.

To all whom it may concern:

Be it known that I, WILLIAM F. HEBRANK, a citizen of the United States of America, residing at Highland, in the county of Madison and State of Illinois, have invented certain new and useful Improvements in Feeding Mechanisms for Can-Making Machines, of which the following is a full, clear, and exact description, reference being had to the accompanying drawings, forming part of this specification.

My invention relates to a mechanism for feeding the can body blanks from which sheet metal cans are to be produced to machines that are utilized in bending the can body blanks into the proper shapes for the bodies of cans and further for the application of the heads to said bodies and the completion of the cans.

My invention has for its object the production of an improved mechanism associated with machines of the kind named, whereby the can body blanks are accurately and positively fed to the machine.

Figure I is a top or plan view of one end of a can making machine and my feeding mechanism associated with said machine. Fig. II is a side elevation of the parts shown in Fig. I. Fig. III is an enlarged vertical cross section taken on line III—III, Fig. II through the feeding mechanism. Fig. IV is an enlarged longitudinal vertical section taken on line IV—IV, Fig. I.

In the accompanying drawings, I have shown a fragment of a can making machine in which the essential features are a frame A, a pair of reciprocally supported dog carrying bars B extending longitudinally of said frame and provided with feeding dogs C adapted to convey the can body blanks X in the forward direction in the machine, side pressure springs D by which the can body blanks are held depressed upon said dog carrying bars, a central strip E and a detent dog F pivoted to the central strip E which is adapted to prevent rearward movement of each can body blank after it has been fed forwardly by the feeding dogs C.

No invention *per se* is herein claimed for the parts of the can making machine which are described.

Referring now to my improved feeding mechanism which is of utility in delivering the can body blanks X to the parts of the machine that have been described: 1 designates the supporting frame of said feeding mechanisms.

2 is a driven shaft journaled in boxes mounted upon the supporting frame 1 and to which sprocket wheels 3 are fixed. 60

4 is an idler wheel shaft mounted upon the supporting frame and upon which are mounted sprocket wheels 5.

6 are the sprocket chains of an endless carrier that are operable upon the sprocket 65 wheels 3 and 5 and which have incorporated therein feeding arms 7 by which the can blanks X are conducted during the travel of the chains 6. The driven shaft 2 that is equipped with the sprocket wheels 3 has power 70 communicated to it through the medium of a bevel gear 8, a bevel gear 9 meshing with said gear 8 and mounted upon a driving shaft 10 that is actuated by a wheel 11 to which power may be communicated in any suitable 75 manner to cause the sprocket chains 6 to operate in conformity to the operation of the blank carrying mechanism in the can making machine to which my feeding mechanism is applied. 80

12 designates inverted U-shaped transverse supporting members having their arms or legs attached to the supporting frame 1 of the feeding mechanism and the horizontal portions of which occupy positions beneath 85 the carrier chains 6 in their upper course of travel. These supporting members have mounted thereon longitudinal supporting strips 13 upon which the chains 6 ride in their upper course of travel and they also 90 serve to support a central rest plate 14 for the can body blanks X that is elevated above the supporting members by posts 15 which rest upon the members 12. The supporting members 12 serve additionally to support 95 longitudinal angular side rest or guide plates 16 for the can body blanks and which are elevated above the members 12 by posts 17 resting upon said members.

In the practical use of my feeding mechanism the feeding mechanism is operated at a speed corresponding to the speed of operation of the dog carrying bars B of the can making machine so that the carrier chains will deliver can body blanks X placed upon the chains and in front of the feeding arms 7 to the dog carrying bars B in order that the dogs C may catch the blanks and start them in their movement through the machine. The feeding arms of the carrier chains are 116

spaced upon said chains in conformity with the spacing of the dogs C upon each dog carrying bar, and as a consequence, the can blanks are each and every one accurately delivered from the feeding mechanism to the dog carrying bars.

I claim:

A feeding mechanism for can making machines comprising a supporting frame, boxes 10 mounted upon the supporting frame, a driven shaft journaled in the boxes, sprocket wheels fixed to the driven shaft, an idler wheel shaft, mounted upon the supporting frame, sprocket wheels mounted upon the 15 idler wheel shaft, sprocket chains having

feeding arms and carried by the sprocket wheels, transverse supporting members having legs attached to the supporting frame, longitudinal supporting strips mounted upon the transverse supporting members, a central rest plate, posts supporting the central rest plate upon the supporting members, longitudinal angular rest plates, and posts supporting the longitudinal angular rest plates upon the transverse supporting members. 20 25

WILLIAM F. HEBRANK.

In presence of—

AD. MEYER,

THEO. ITTUE.
